UNITED STATES PATENT OFFICE.

FRANK E. SCHARTOW, OF RACINE, WISCONSIN, ASSIGNOR OF ONE-HALF TO RUPERT A. NOURSE, OF MILWAUKEE, WISCONSIN.

SNAP-HOOK.

1,245,275.

Specification of Letters Patent.

Patented Nov. 6, 1917.

Application filed June 19, 1915. Serial No. 35,014.

To all whom it may concern:

Be it known that I, FRANK E. SCHARTOW, a citizen of the United States, and resident of Racine, in the county of Racine and State of Wisconsin, have invented new and useful Improvements in Snap-Hooks, of which the following is a description, reference being had to the accompanying drawings, which are a part of this specification.

10 This invention relates to improvements in snap hooks of that type in which the hooks are formed of cast metal and in which the hook portion is cast in an angular position and is straightened in assembling the parts.

15 In the manufacture of snap hooks the hooks are cast at an angle with relation to the shanks to eliminate the use of expansive cores in the foundry, and the hook portions are then bent to aline with the shanks. In some forms of hooks the shanks are provided with projecting lips which are bent over pivot pin portions of guard tongues to pivotally connect the tongues to the shanks, and in other constructions the guard tongues

20 are pivoted to the shank portions by pivot pins which are extended through holes drilled in the shanks and the tongues and the ends of the pins are riveted to the parts.

25 All of the parts of the hooks before being assembled are usually put into a tumbling barrel and tumbled to remove the rough edges and smooth the castings. During this tumbling process the projecting ears are very often considerably and materially weakened 30 to such an extent as to break while being bent over the tongue portions or when in use.

Furthermore in many forms of hooks the guard tongues are provided with guard portions which subject the tongues to longitudinal strains and these strains are usually borne by the projecting lips or the pivot pins and as these parts are comparatively weak they often break in use.

45 Furthermore during the tumbling process some of the parts are worn to such an extent that when assembled there is so much play between the parts as to form snap hooks of inferior quality.

50 It is one of the objects of the present invention to overcome the before mentioned objectionable features and provide a snap hook in which the use of projecting pivot lips or pivot pins is eliminated.

A further object of the invention is to 55 provide a snap hook in which the necessary bending of the hook portion to alined position with relation to the shank serves to lock the assembled portions of the snap hook together, thus eliminating many operations 60 necessary in other forms of hooks.

A further object of the invention is to provide a snap hook having means for relieving the pivotal connection of the tongue with the shank of endwise thrust against the 65 tongue.

A further object of the invention is to provide a snap hook which is of simple construction, is strong and durable and is well adapted for the purpose described.

With the above and other objects in view the invention consists of the improved snap hook and its parts and combinations as set forth in the claims, and all equivalents thereof.

75 In the accompanying drawing in which the same reference characters indicate the same parts in all of the views:

Figure 1 is a side view of the improved snap hook;

Fig. 2 is a longitudinal sectional view of the hook;

Fig. 3 is a top view thereof, the view also indicating by dotted lines the angular position of the hook before it is bent into alined position with relation to the shank; and

Fig. 4 is a sectional detail view of a portion of the hook taken on line 4-4 of Fig. 2.

Referring to the drawing the numeral 8 indicates the shank, 9 the hook portion, 10 the eye and 11 the guard tongue pivotally connected to the shank. The shank portion of the hook adjacent the eye is provided with upstanding parallel side ears 12 which are joined together at their upper portions by 95 an integral transversely extending pivot bar 13 which is of circular form in cross section. The portion 14 of the shank immediately below this pivot is open to permit casting without the use of expensive cores and 100 the hook portion 9, as indicated by dotted lines 9', is cast at an angle with relation to the shank portion for the same purpose.

The forward edges 15 of the upstanding ears are curved concentrically with relation 105 to the pivot bar 13. The guard tongue 11 is positioned between the ears 12 and is provided with a semicircular rear portion 16

which engages and partly surrounds the lower portion of the transverse pivot bar 13 and forms a pivotal connection therebetween. The tongue is also provided with offset downwardly extending curved guard projections 17 having their rear offset edges 17' concentric with and engaging the curved edges of the upstanding ears 12 to take the end thrust of the tongue. The forward reduced end portion 18 of the tongue extends beneath the end of the hook and into a recess 19 formed in said hook end, and the tongue is protected by the side flanges 19' of said hook.

15 A coiled spring 20 interposed between the shank and a medial portion of the tongue serves to hold the tongue yieldingly in engagement with the hook end and the transverse pivot bar 13. The tongue is provided 20 with a boss 21 which is engaged by the upper convolution of the spring and the shank is provided with a recess 22 to receive the lower end of the spring to hold said spring in position.

25 As the spring is located closer to the transverse pivot bar than to the free end of the tongue, the free end will naturally swing forwardly to open position, when pressed to permit the entrance of a member to be engaged by the hook. In swinging to open 30 position the guard projections will swing downwardly on each side of the shank.

In assembling, it is only necessary to insert the curved pivot portion of the tongue 35 beneath the transverse pivot bar, then insert the spring in position press the free end of the tongue downwardly and then twist the hook portion to aligned position with the shaft.

40 When the hook portion has been thus twisted the guard tongue and spring will be non-removably locked to the shank.

From the foregoing description it will be seen that the snap hook is of very simple 45 construction, is strong and durable and is well adapted for the purpose described.

What I claim as my invention is:

1. A snap hook, comprising a shank provided with a hook portion which while initially at an angle with relation to the shank 50 extends in a line parallel to the shank and also having opposite upstanding ears connected together by a transverse bar, an inwardly movable tongue guard extending between the ears and having a 55 curved portion which extends beneath and partly surrounds the transverse bar, said tongue also having curved downwardly extending guard projections which straddle 60 the shank and bear against portions of the upstanding ears, said shank and said tongue guard provided with spring holding means, and a coiled spring interposed between the tongue guard and the shank and engaging 65 the spring holding means, said tongue guard

and spring being locked to the shank by the hook portion being positioned in the path of removal movement of the tongue.

2. A snap hook, comprising a shank having a hook portion and upstanding opposite ears connected together by a transverse bar, the forward edges of said ears being curved concentrically with relation to the transverse bar, an inwardly movable tongue guard extending between the ears and pivotally 75 engaging the transverse bar and having offset portions which engage the curved edges of the ears, the forward end portion of the tongue engaging the end of the hook portion, and a spring interposed between 80 the tongue guard and the shank.

3. A snap hook, comprising a shank having a hook portion and upstanding opposite ears connected together by a transverse bar, the forward edges of said ears being curved 85 concentrically with relation to the transverse bar, an inwardly movable tongue guard extending between the ears and having a curved rear portion which partly surrounds the transverse bar and an offset portion which engages the curved edges of the ears, the forward end portion of said tongue engaging the hook end, said tongue and shank having spring holding means, and a coiled spring interposed between the shank 95 and the tongue and engaging the holding means.

4. A snap hook, comprising a shank having a hook portion provided with a recess at its end, said shank on its opposite sides 100 also having upstanding ears of greater width than the shank connected together by a transverse bar and also having a spring recess between the ears, the forward edge portions of said ears being curved concentrically with relation to the transverse bar, an inwardly movable tongue guard extending between the ears and having a curved rear portion which partly surrounds the lower portion of the transverse bar and also having offset curved portions which engage 110 the curved edges of the ears, the forward edge portion of the tongue entering the recess of the hook end, said tongue also provided with a projecting spring holding portion, and a coiled spring extending into the recess of the shank and engaging the projection of the tongue.

5. A snap hook, comprising a shank having a hook portion provided with a recess 120 at its end, said shank on its opposite sides also having upstanding ears of greater width than the shank and connected together by a transverse bar and also having a spring recess between the ears, the forward edge portions of said ears being curved concentrically with relation to the transverse bar, an inwardly movable tongue guard extending between the ears and having a curved rear portion which partly surrounds the 125

lower portion of the transverse bar and also having downwardly extending portions which straddle the shank, the rear edge portions of the downwardly extending portions being curved and bearing against the curved edges of the upstanding ears and the forward end of the tongue entering the recess of the hook end, said tongue also provided with a projecting spring holding portion,

and a coiled spring extending into the recess 10 of the shank and engaging the holding projection of the tongue.

In testimony whereof, I affix my signature, in presence of two witnesses.

FRANK E. SCHARTOW.
